UNITED STATES PATENT OFFICE

HOWARD PARKER, OF BERLIN, NEW HAMPSHIRE, ASSIGNOR TO BROWN COMPANY, OF
BERLIN, NEW HAMPSHIRE, A CORPORATION OF MAINE

ELBOW LATHE

Application filed March 12, 1929. Serial No. 346,478.

This invention relates to mechanism for truing the ends of pipe elbows and shaping these ends to fit a threaded, tapered, or other kind of coupling, as desired. The apparatus 5 hereinafter described is more especially intended for use in operating on elbows of fiber tubing or conduit such for example as is made by winding up a web of wet cellulosic fiber on a mandrel until the desired wall thickness is obtained, then removing the tube 10 thus formed from the mandrel, and drying the tube. The dried tube may then be treated with a waterproofing compound such as pitch, this resulting in a tube which is 15 relatively light in weight, but strong. The ends of the tube sections may be machined to receive corresponding couplings. Some 20 of the tube sections may be bent, while wet, into elbows of various angles. In machining the ends of an elbow to receive couplings, it is important that the ends be properly aligned with the adjoining conduit sections to avoid undue stresses at the joints. To 25 this end I provide a pair of end-trimming mechanisms carried by a supporting frame so as to operate about axes which bear a definite angular relation to each other. Suitable means for supporting an elbow for trimming may also be carried by the frame.

30 Various additional advantageous features of structure will be apparent to one skilled in the art from the description of the invention which follows hereinafter, and from the drawings, of which,

Figure 16 is an end elevation of a cutter 65 head for operating on the exterior surface of a tube.

Figure 17 is a side elevation of the same.

Referring to the drawings in detail, 20 represents a bed having the general shape of a quadrant. At one side of this quadrant is an extension 21 of the bed on which is mounted a frame 22. At the other end of the bed 20 is a second frame 23 which is carried by an arm 24 pivoted as at 25, this pivot being 70 at the center of the quadrant formed by the bed 20. The frames 22 and 23, as shown in Figure 1, may be arranged so that their long axes are perpendicular to one another. The frame 23, however, can be swung on the pivot 75 25 so that the axes of the frames may be adjusted to any angle from 90° to 180°.

On the frame 22 may be mounted a cutter head 26, a similar cutter head 27 being mounted on the frame 23. These cutter heads may be driven in any desired manner. As shown on the drawings, the cutter head 26 is rotated as by an electric motor 28, a similar motor 29 being provided to drive the cutter head 27. The cutter heads 26 and 27 are preferably so mounted that their axes of operation are respectively parallel to the axes of the frames 22 and 23.

In order to provide for quick movement of the cutter heads along their axes toward and from the work, each cutter head together with its driving mechanism may be mounted on a longitudinal slide 30, which is provided with a rack 31 and may be controlled as by a suitable hand wheel 32. The cutter heads 100

are each adjustable in a horizontal plane to operate on elbows of different lengths. To this end the slide 30, as shown, is slidably supported by a transverse slide 33 which slides 5 transversely on a standard 34, the standard 34 in turn being adjustable longitudinally on the frame 22. The positions of the slides 33 and 34 may be adjusted as by a transverse screw threaded member 35 and a longitudinal 10 screw threaded member 36. The screw 35 is carried by the slide 34 and engages an internally threaded lug 37 which is carried by the slide 33 so that rotation of the screw 35 moves the slide 33 laterally of the frame 22. In like 15 manner the screw 36 is carried by the frame 22 and engages an internally threaded lug carried by the standard 34 so that rotation of the screw 36 results in longitudinal adjusting movement of the standard 34 and the 20 mechanism carried thereby.

In order to facilitate the rotation of the screws 35 and 36, I may provide simple gearing such as is illustrated in Figure 7, this 25 gearing comprising a gear 38 which meshes with a pinion 39, the latter being fixed to a short shaft 40 having a squared end 41 to receive an operating crank. The gears 38, 39 may be enclosed in a suitable casing 42 to protect them from dust and dirt. Similarly 30 on the frame 23 the cutter head 27 may be mounted on a slide 30 which is longitudinally movable as by a rack 31 and an operating wheel 32, the slide 30 being supported by a transverse slide 33 and a standard 34, which 35 are respectively adjustable as by screws 35 and 36 in the same manner as hereinbefore described.

In order to support the work securely in proper position for operation, I may provide 40 with the cutter heads a pair of clamps each of which is preferably adjustable in a plane perpendicular to the axis of its adjacent cutter head so as to engage elbows of any diameter within the range of the mechanism. As 45 shown in Figure 2, the frame 22 may have fixed at the forward end thereof a suitable standard 43 on which is mounted a vertical slide 44, the height of which may be conveniently adjusted as by a pair of screws 45 which 50 may be operated by a hand wheel 46 through suitable gearing 47. This vertical slide 44 carries a horizontal slide 48 which may be horizontally adjusted thereon as by a screw 49 rotatable by a hand wheel 50. Manipulation 55 of the hand wheels 46 and 50 thus makes possible any desired adjustment of the clamp in a plane perpendicular to the axis of operation of the cutter head 26.

As shown in Figure 4, the work may be 60 clamped between the top surface of the slide 44 and the under face of a clamping member 51, which is movable vertically with respect to the slide 44. In order to effect a quick clamping action, the clamping member 65 51 may be carried at the lower end of a stem

52 which is supported by a block 53. The stem 52 may be provided with a shoulder against which a washer 54 may be pressed as by a spring 55 in such a manner as to press the clamping member 51 upwardly. In order to 70 move the clamp 51 downwardly to clamping position, I may provide a cam member 56 pivoted on a suitable pin 57 and adapted to bear on the upper end of the stem 52. An operating lever 58 may be fixed in the clamp 75 block 56 so that when the block is swung through an angle of 90° the stem 52 is pushed downwardly thereby for a definite distance, thus forcing the member 51 downwardly into clamping engagement with a pipe there- 80 under.

A similar clamp may be mounted in front of the cutter head 27. As shown in Figures 1, 2 and 3 this clamp may be carried by a standard 75, the upper face of this standard 85 serving as the lower jaw of a clamp, of which the upper jaw 51 is operative as illustrated in Figure 4, this upper jaw being transversely adjustable as by a hand wheel 50 which operates a screw 49. The standard 75 may 90 be vertically adjusted as by a vertical screw on the end of which is mounted a suitable hand wheel 76. This screw, together with the standard 75, may be supported on a horizontally movable slide 77, which is transversely adjustable by a horizontal screw 78 supported on the end of the frame 23. The structure of the clamping mechanism may be identical with that illustrated in Figure 4 and described in detail. 100

The block 53 is preferably mounted for ready vertical adjustment in order to accommodate pipes of different diameters. To this end the slide 48, which supports the clamp, may have a vertical slot 59 therein. On either side of this slot I provide a serrated surface 60 having teeth adapted to engage with similar teeth in the rear face of the block 53. The block 53 may be clamped in adjusted position against the serrated surface 60 as by a bolt 61 which passes through the slot 59 and through a portion of the block 53. On the head of the bolt 61 is pivotally mounted a pair of ears 610, the edges of which form cam surfaces which bear on the rear face of the slide 48. The ears 610 may rotate on a pin 611 extending through the head of the bolt as by a handle 63. A nut 62 on the opposite end of the bolt 61 may be adjusted so that movement of the ears 610 to the position shown in Figure 4 clamps the block 53 tightly against the serrated face 60. When the handle 63 is swung upwardly, the block 53 is at once released and may be manually raised or lowered as desired. 115

When the mechanism as a whole is in the position illustrated in Figure 1, it is ready to operate on a 90° elbow, the axes of the portion of the cutter heads 26 and 27 being at right angles. It may be desirable, 120

however, to trim and shape the ends of elbows having lesser bends. Such elbows ordinarily are made with bends of certain standard angles only, such as 60°, 45°, and 30°. In order to facilitate the adjustment of the mechanism to operate on elbows with angles of these sizes, the bed 20 may be provided with suitably located holes 64 to receive a locking pin 65 (Figure 3) so as to hold the frame 23 securely in place when it has been swung on the pivot 25 to one of the standard angles.

The frame 23 and the mechanism carried thereby may be rotated to adjusted position as by an arcuate rack 650 with which engages a suitable pinion 66. As shown in Figure 5, the pinion 66 may be fixed to or formed on the end of a shaft 67, a ratchet wheel 68 being mounted on the upper end of the shaft 67. Cooperating with the ratchet wheel 68 is a pawl 69 which is pressed against the wheel 68 as by a suitable spring 70. A pin 71 extends through the pawl 69 and projects out from the housing enclosing this portion 25 of the mechanism. The pin 71 works in a slot 72 whereby the pin and pawl may be retracted from the ratchet wheel 68. The housing 73 which encloses the ratchet wheel 68 and in which the pawl 69 is mounted is also provided with a recess to receive a suitable handle 74 by which the ratchet may be rotated so as to swing the frame 23 around its pivot 25. As soon as the pin 650 has reached the desired hole 64, the frame 23 may thereupon be locked in position.

The cutter heads 26 and 27 may be each connected to their respective motors 28 and 29 as by suitable gearing which is capable of automatically reversing and stopping. This connecting gearing may be identical for both cutter heads so that a description of one will serve for both. Referring to Figures 8 and 9, the shaft 79 from the motor rotates a pinion 80 which meshes with a gear 81. This gear is secured to a coaxial pinion 82 and is loosely mounted with it on a shaft 83. The pinion 82 meshes with a gear 84 loosely mounted on a parallel shaft 85 with a coaxial pinion 86 which meshes with a gear 87. A pinion 88 is coaxial with and secured to the gear 87, both being loosely mounted on the shaft 83. The pinion 88 meshes with a gear 89 which is fixed on the shaft 85. Also mounted on the shaft 85 is a gear 90 which meshes with a gear of similar size mounted on the shaft 83 so that the train of gearing thus far described operates to drive the shafts 83, 85 at equal speeds in opposite directions. The shaft 85 terminates with the gear 90 and abuts a drive shaft 92 a portion of which may be squared or splined to rotate a clutch member 93 axially slidably thereon. This clutch member is adapted to engage a corresponding member on the face of the gear 90 so that when these members are engaged as shown in Figure 8,

the shaft 92 is rotated with the shaft 85. A portion of the shaft 83 may be squared or splined to rotate a clutch member 94 axially slidably thereon. This clutch member is adapted to engage a corresponding member 70 on the face of a gear 95 which is loosely mounted on the shaft 83. The gear 95 meshes with a pinion 96 which in turn meshes with a gear 97 equal in size to the gear 95 and mounted on the shaft 92. Thus when the clutch member 94 engages the pinion 95, the shaft 92 is driven in the same direction as the shaft 83, this being opposite to the direction of rotation of the shaft 85. Suitable means may be provided for sliding the clutch members 80 93, 94 into and out of engagement with their respective gears 90, 95, such operating means including a lever 106 which may be rocked as by a handle 98.

The drive shaft 92 connects the cutter head 85 mechanism with the transmission gear and is provided with a threaded portion 99 on which rides a nut 100 having a downwardly extending arm 101 which slides on a pair of rods 102 between adjustable abutments 103 and 104. The rods 102 are extensions of a rod 105 which projects from the gear casing. During the rotation of the screw 99, the nut 100 travels in one direction or the other until its arm 101 engages one of the abutments 103, 104 according to its direction of travel. Thereafter the rod 105 is moved endwise to rock the clutch shifting lever 106. This clutch lever has a downwardly projecting portion 107 which is longitudinally bored to receive a plunger 108 behind which is a spring 109. The outer end of the plunger may be beveled as shown in Figure 12 and rests against a sloping shoulder 110 of a cam member 111 which is adjustably secured to the bottom of 105 the transmission gear casing. The inner end of the rod 105 is longitudinally bored to receive a plunger 112 behind which is a spring 113. The spring 113 tends to push the plunger 112 out of the bore, the plunger being retained therein as by a suitable pin 114. Opposed to the plunger 112 is a shorter plunger 115 carried in the end of a bridge member 116 and backed by a suitable spring 117 which tends to press it in a direction opposite to the plunger 112. As shown in Figures 12 and 13 the plungers 112 and 115 are thus opposed to each other and press in opposite directions against opposite sides of the extension 107 of the clutch operating lever 106.

If the mechanism has started in operation from the position illustrated in Figures 9 and 12, the nut 100 travels toward the right until it reaches the abutment 103 whereupon its further travel pushes the rod 105 toward the right. Since the lower end of the plunger 108 rests against the cam surface 110, it will be necessary for the plunger 108 to ride upwardly thereon against the pressure of the spring 109 before the clutch operating lever 130

106 can be swung from the position shown in Figure 12. On account of the resistance offered by the spring 109 motion of the rod 105 at first causes compression of the spring 113 since the plunger 112 is resting against the side of the unmoved extension 107 of the clutch-actuating lever. The motion of the rod 105 likewise retracts the plunger 115 from contact with the opposite side of the extension 107 so that when the spring 113 is sufficiently compressed to overcome the resistance of the spring 109, the plunger 108 rides up on the cam shoulder 110, whereupon the motion of the extending spring 113 snaps the extension 107 toward the right until the lower end of the plunger 108 rests in a depression 118. The swing of the lever 106 from the position shown in Figure 12 to a position wherein the plunger 108 rests in the depression 118 is sufficient to disconnect the clutch 95 and to connect the clutch 97 so that the rotation of the connecting shaft 99 is automatically reversed and the nut 100 starts traveling toward the left. This travel continues until the arm 101 of the nut engages the abutment 104 so as to move the rod 105 toward the left. This results in a compression of the spring 117 which is shorter than the spring 113. When the travel of the rod 105 toward the left is sufficient to displace the plunger 108 from the depression 118, the plunger 115 is only of sufficient length to push the extension 107 far enough to the left for the plunger 108 to enter a second depression 119. When the plunger rests in this depression, the lever 106 is in its neutral position, that is, neither clutch is engaged, hence the drive of the cutter head automatically stops. In this manner, it is only necessary to start the operation of the cutter head on each pipe end to be trimmed. Once started thus, the cutter head will travel the full extent in one direction, will be automatically reversed so as to travel back to its starting point whereupon the rotation thereof will automatically stop.

The cutter heads 26 and 27 are of a type designed to carry a tool around stationary work, the heads being adjustable so that the tool will operate on pipes of different diameters. The cutter head shown in Figures 14 and 15 is designed for work on exterior surfaces of pipe ends, this cutter being adapted to trim the outer surface of the pipe end to a suitable taper. The mechanism by which the tool is carried is similar in principle to that described in detail in my co-pending application Serial No. 136,784, filed September 21, 1926.

60 The cutting head may be supported on a suitable bracket 120 in which is journaled a suitable gear 121 fixed to the shaft 92. The gear 121 meshes with a gear 122 which is keyed to a hollow shaft 123. On the end of this shaft is fixed a transversely extending

arm 124 which is longitudinally slotted as at 125 to receive a bolt 126 by which a suitable block 127 may be clamped in adjustable position on the arm 124. A suitable counterweight 128 may be formed on or secured to the arm 124 at the end remote from the slot 125 so as to counterbalance to some extent the block 127 and the tool carriage 129 carried thereby. The block 127 is provided with a slot 130 in which the tool carriage 129 may travel, the block being so adjusted that the slot 130 is inclined with reference to the direction of the axis of rotation so that as the tool carriage 129 is fed therealong, the tool cuts a conical surface on the end portion of the work. By loosening the bolt 126, the block 127 with the tool carriage may be moved readily inwardly or outwardly on the arm 124 to operate on work of different diameters. In order to facilitate the adjustment of the block 127 a suitable abutment member 131 may be mounted thereon to engage the end of a rod 132 which is secured at its further end to the counterweight 128.

As shown in Figure 15, a face of the counterweight may be grooved as at 133 and a rack 134 bolted thereto. A block 135 having teeth corresponding to the teeth of the rack 134 may be bolted to the rack. The teeth of the rack 134 are preferably spaced by a unit distance such as an inch so that each adjustment of the block 135 on the rack must be a whole number of inches. Even adjustment of the rod 132 may be made as by a knurled nut 136 carried in the block 135 and in threaded engagement with the lower portion of the rod 132, this portion being slotted as at 137 and splined to prevent rotation of the rod in the block.

In setting the tool block 127, it may be first moved radially outwardly, then the position of the rod 132 may be adjusted according to the diameter of the work to be operated upon, after which the block 127 may be moved inwardly until the abutment 131 engages the end of the rod 132. The bolt 126 may thereupon be set up tightly to clamp the block 127 in position on the arm 124. Rotation of the arm 124 about the axis of the work will carry therewith the tool 138, this tool being removable fixed in a suitable slide 139 which is adjustably attached to a downwardly projecting portion 140 of the tool carriage 129.

As the arm 124 swings the tool carriage 129 about the axis of the work, the carriage may be fed along the slide 139 by a screw shaft 141 with which the carriage is in threaded engagement. The screw shaft 141 is rotated by a suitable train of gears 142, 143, 144 and 145. The gears 142, 143 and 144 are mounted in a suitable casing 146 which is adapted to swing as a unit around the axis of the work together with the arm 124. The gear 145, however, is fixed against rotation by being keyed or otherwise secured to the

casing which forms a part of the bracket 120 so that as the housing 146 revolves around the axis, the gear 144 has a planetary motion about the stationary gear 145 and is rotated thereby, this rotation being transmitted to the gear 143 and thence to the gear 142, the feed shaft 141 being connected to the latter. The housing 146 is provided with a suitable slot 147 in its side walls so that when the block 127 is moved radially inwardly or outwardly, the gear 142 is also moved an equal amount by the shaft 141. A pair of suitable plates 148 extend loosely around the shaft 123 and the bearing shaft of the gear 144 so that the gear 144 is retained in meshing relation with the gear 145 for all positions of the casing 146. Since the gears 142, 143 and 144 are all journaled in the casing 146, their relative position is thus maintained constant so that the gear 142 is maintained in operative relation for the gear 145 for all positions of the housing 146. Thus as arm 124 carries a cutting tool 128 about the work, this tool may be fed by the feed shaft 141 which is driven through the gear train as described.

Figures 16 and 17 illustrate a similar cutting head except that the tool carriage 129 supports a slightly different type of tool holder 149 on which is mounted a suitable tool 150 adapted to trim the inner surface of the work. Since the taper on the inner surface is opposite from that on the outer surface, it will be observed that the angle of travel of the carriage shown in Figure 17 is different from that of the carriage shown in Figure 15. The mounting of the tool carriage on the arm, the means for adjusting the tool carriage radially, and means for feeding the tool carriage along the work may be all identical with those described hereinbefore in connection with the cutter head illustrated in Figures 14 and 15.

In operating on an elbow, the frame 23 may first be fixed at the desired angle with reference to the frame 22, a right angle being shown in Figure 1. The standards supporting the cutter heads and their driving mechanisms may then be suitably adjusted so as to be properly spaced from one another. The work holding clamps may then be adjusted if necessary so that the centers of the ends of the work will be suitably aligned with the axis of rotation of the tool. In order to center the cutting heads to the ends of the work, each cutting head may be backed off by manipulation of the hand wheel 32. If the cutter head is for operation on the outer surface of the work, as in Figure 15, a centering cone 151 may be mounted on the forward face of the arm 24, this cone being held in place as by a stem 152 which enters the open end of the hollow shaft 123. The hand wheel 32 may then be turned to advance the cutter head until the end of the cone 151 enters the work and properly centers it. Thereupon the various adjustable parts of the mechanism

are suitably adjusted so that the cutter heads are properly aligned with their respective clamps. The cutter heads may then be backed off to permit the removal of the centering cones, whereupon the heads are again advanced to operative position.

If the cutter head is designed for operation on the inner surface of the work, a centering cone 153 may be mounted in such a way as not to interfere with the tool holder 149. As shown in Figure 17 the cone 153 may be supplied with an offset stem 154 adapted to slip into a recess in a boss 155 formed on the counterweight 128.

Having thus described an embodiment of this invention, it should be evident to those skilled in the art that various changes and modifications might be made therein without departing from its spirit or scope as defined by the appended claims.

I claim:

1. Apparatus of the class described comprising a pair of cutter heads for trimming the ends of a pipe elbow, means for revolving each cutter head around an axis, means for supporting the cutter heads with their axes intersecting, means for clamping a pipe elbow from above and below at points adjacent to the ends thereof, each clamp being vertically adjustable relatively to its respective cutter head.

2. Apparatus of the class described comprising a horizontal bed, a vertical pivot thereon, means for supporting a pipe elbow with its curvature approximately concentric with the axis of said pivot, a cutter head mounted for operation on one end of an elbow thus supported, and a second cutter head swingable about said pivot and mounted for operation on the other end of said elbow.

3. Apparatus of the class described comprising a horizontal bed, a vertical pivot, a pair of frames adjustable with respect to each other about said pivot, a cutter head on each said frame revoluble about a horizontal axis perpendicular to the radius from said pivot, and means for holding a pipe elbow with its ends aligned respectively with the axes of revolution of said cutter head.

4. Apparatus of the class described comprising a horizontal bed, a vertical pivot thereon, a frame fixed to said bed, a cutter head mounted on said frame revoluble about an axis perpendicular to a radius from said pivot, means for adjustably moving said cutter head along its axis and horizontally at right angles thereto, an arm extending horizontally from said pivot and swingable thereon, and a second cutter head carried by said arm.

5. Apparatus of the class described comprising a horizontal bed, a vertical pivot thereon, a frame fixed to said bed, a cutter head mounted on said frame and revoluble about a horizontal axis, an arm swingable

about said pivot, said arm being parallel to but offset from a radius from the pivot, and a second frame and cutter head carried by said arm, said second cutter head being ⁵ rotatable about a horizontal axis perpendicular to said radius.

In testimony whereof I have affixed my signature.

HOWARD PARKER.
